UNITED STATES PATENT OFFICE.

HARRY H. STYLL, OF SOUTHBRIDGE, MASSACHUSETTS.

LENS.

1,364,960.

Specification of Letters Patent. Patented Jan. 11, 1921.

Application filed December 9, 1919. Serial No. 343,536.

To all whom it may concern:

Be it known that I, HARRY H. STYLL, a citizen of the United States, residing at Southbridge, in the county of Worcester and 5 State of Massachusetts, have invented certain new and useful Improvements in Lenses, of which the following is a specification.

My invention relates to improvements in lenses and has particular reference to ophthalmic lenses formed from two or more 10 pieces of material.

One of the leading objects of the present invention is the provision, as an article of manufacture for commercial sale, of an improved 15 form of lens blank or semi-finished lens, and of an improved process for producing the semi-finished and the completed lens.

A further object of the present invention resides in the provision of a novel process of 20 forming a two-part bifocal lens which will enable me to produce a two-part bifocal lens, in which the two parts are ground to form a single continuous surface after being joined one to the other, but which are capable 25 of separation after grinding at any time as may be desired.

A further object of my present invention is the provision of an improved two-part lens in which the surface on which both 30 parts are exposed may be ground or finished by the manufacturer, and which may then be sold to the trade for finishing of the other side, in such condition that it may be handled as an ordinary lens by the shop man 35 without any liability of injuring or separation of the two parts of the lens during the subsequent grinding and finishing of the lens.

A further object of the present invention 40 is the provision of means for protecting the segment or supplemental lens portion secured to the main blank to prevent it so sticking to the block on which it may be mounted for future grinding as to render it 45 liable to be loosened or detached by the jar incident to removal of the lens from the block, while permitting of the firm supporting of the segment bearing portion of the lens, while mounted on the block, if desired. 50 Other objects and advantages of my improved lens and process of constructing the same should be readily apparent by refer-

ence to the following specification taken in connection with the accompanying drawings forming a part thereof, and it will be understood that I may make any modifications in the specific details of construction shown and described within the scope of the appended claims without departing from or exceeding the spirit of my invention. 60

Figure I represents a plan view of one of my commercial semi-finished blanks.

Fig. II represents an edge view thereof.

Fig. III represents a sectional view of the major blank illustrating one step in my 65 process.

Fig. IV represents a similar view of the segment illustrating a further step in the process.

Fig. V represents a sectional view of the 70 segment united to the main blank in condition for grinding.

Fig. VI represents a similar sectional view illustrating the grinding of the first or bifocal surface of the blank. 75

Fig. VII represents a sectional view of the semi-finished blank provided with my improved segment protector.

Fig. VIII represents a sectional view showing the protected blank mounted on a 80 block.

Fig. IX represents a similar view illustrating an alternative step in my process.

Fig. X represents a sectional view of the 85 finally ground lens mounted on the block.

Fig. XI represents a view of the completely formed lens, the blank from which the same was cut being indicated in dotted line.

In the drawings, in which similar characters of reference are employed to denote corresponding parts throughout the several views, the numeral 1 designates as an 90 entirety the major portion of the lens or blank adapted to be provided during the finishing thereof with the anterior curve 2.

In the carrying out of my invention I first form, preferably in the anterior face of the blank 1, the countersink or recess 4, which is formed to desired necessary curve to exactly receive the curved face 5 of the segment or button 6, which is adapted to be secured in the recess 4. It will be understood that, as hitherto has been known in the 100

art, the blank 1 and segment or button 6 are formed from glass of different indices of refraction, the index of refraction and the curves 4 and 5 being so figured as to give the 5 desired reading addition to the blank so that in the final lens the visual effect through the button and countersink will have a desired increased value or addition, the curves ground on the posterior and anterior surfaces of the blank producing various desired 10 foci in the finished lens, but the power through the countersink or segment always varying by a predetermined known amount from the prescriptive value through the 15 major portion of the lens.

In the carrying out of my invention the members 1 and 6 having been prepared as illustrated in Figs. III and IV, the next step is to suitably secure the parts together.

20 In accomplishing this I preferably employ a suitable heat actuated cement, warming the parts to be united and warming the cement itself to a suitable working temperature, and then quickly and firmly pressing 25 the parts together so that the button or segment will be securely retained in the countersink with as thin as possible a retaining film between the curves 4 and 5. The parts when united will then present substantially 30 the appearance of the blank illustrated in Fig. V, the button 6 projecting somewhat outwardly beyond the countersink, it being necessary to suitably grind away the button during the next step in my process.

35 The next step in the process of manufacture of my improved bifocal is illustrated in Fig. VI. It will be noted by a comparison of Figs. V and VI that in this step the outer or anterior curve 2 is formed on the 40 blank, in the formation of this curve a portion of the button 6 being ground away so that a continuous curve extends across the entire front face of the semi-finished blank and the line of joinder between the blank 45 and segment on account of the simultaneous grinding of the parts and formation of the single continuous curved surface is rendered practically invisible so that the parts present the appearance of a single continuous 50 structure rather than a pronounced line, as has hitherto been experienced when it was attempted to separately grind the button and the lens and then merely fit the button into the countersink without subsequent 55 grinding of the parts.

It will be understood that in the formation of a lens of this type it is always desirable to first form the bifocal curve and that it is preferable that the bifocal, or in the 60 present instance, the anterior curve, be ground by the manufacturer of the lens, since it is in connection with this grinding, if at all, that difficulties in the manufacture of the lens, imperfections and the like, are 65 brought out, while the opposite face of the

lens being a single plain piece of glass can satisfactorily be ground by the shop man and by suitable variance in the curve on the ocular side the desired prescriptive value of the lens produced.

70 In either event, however, it is necessary, after the bifocal side of the lens has been ground, to mount the lens on a suitable block 7, retaining it in place on the block by the use of a pitch or similar adhesive medium 8, 75 and to then grind the second surface of the lens.

In those cases where it is desired to sell and ship the blank especially and also in the regular manufacture of the blank, it is necessary for the obtaining of best results, that some means be provided for protecting the segment and absolutely preventing accidental loosening of the same during the second grinding operation or during the loosening of the lens from the adhesive 8 after the grinding has been completed. In fact it is at this point that considerable difficulty might be otherwise experienced in the formation of this type of bifocal, since while 90 the cement connecting the major blank and segment is sufficient to retain the segment under all ordinary conditions, on account of the fact that a cement has been employed which will permit of subsequent separation 95 of the parts, if desired, the parts are not absolutely permanently or fixedly united, as would be the case were they fused or similarly attached. In removing a lens from a

100 block such as the block 7 or the like, it is customary in the trade to loosen the lens either by picking, that is by prying with a sharp instrument under one edge, or by giving one or more sharp blows or raps to the block, the jar breaking the hold between the pitch or retaining medium 8 and the lens without the liability of breakage of the lens or pulling pieces off the lens, as might occur were it attempted to simply pull off the lens. Naturally this jar, sufficient to break the adhesion of the substance 8 to the entire body of the lens, would have a tendency to loosen the engagement of the segment with the main blank so that there would be a possibility of the segment being either loosened 110 by the jar or pulled loose in case the lens were picked off on account of the opposed adhesive action of the cement on the one side of the segment and the adhesive 8 on the opposite side of the segment working to pull 115 the segment in opposite directions. One of the purposes of my present invention, therefore, is the protection of the segment in such manner that the adhesive 8 will not act 120 thereagainst, and the consequent tendency to loosening of the segment during the second grinding operation largely eliminated.

In the accomplishment of this result I preferably apply to the segment and immediately contiguous portion of the major 125

blank, a protecting coating or covering 9, which will serve to prevent the pitch or adhesive 8 from adhering to the segment.

This coating may be either of cloth, paper 5 or the like, lightly stuck onto the face of the lens, or may be a heavy solution of whiting, paraffin or other substance which will prevent the pitch from adhering.

While I preferably apply this coating 10 direct onto the lens, on account of the fact that a lens thus prepared may be readily placed on any ordinary block in the customary manner of mounting lenses without any special care being observed, it will be understood 15 that if preferred, as in the case of large establishments having a great deal of this work to do, the block may be prepared to receive the lens in place of the lens being prepared to fit on the block, this being considered 20 by me an equivalent alternative step in my present process.

This alternative step in my process, I have illustrated in Fig. IX, in which I have shown the pitch as indented, relieved or removed at 10, so that a recess is formed spanning the segment 9 so that there is no pitch at this point which could adhere to the segment. The only disadvantage here present is that the lens is not as thoroughly supported 30 for the grinding of the second surface and that more care must be observed in the mounting of the lens on this type of block, although very satisfactory results may be obtained in this manner.

In both forms the general result obtained 35 is the same, however, that the pitch or the like is prevented from adhering to the button or segment 6, while the coating 9 also serves to an extent as a heat insulator when 40 the lens is being mounted on the hot pitch, and prevents any possibility of loosening of the retaining cement on account of the conducted heat.

The lens having been mounted with the 45 button protected as described, it is then merely necessary to grind the necessary prescription curve thereon, after which the lens is removed from the block, the protector 9 removed from the segment if the 50 same has not remained adhering to the pitch, and the lens cut into final finished form. It will be understood, however, that if preferred to thus protect the more delicate reading portion or segment of the lens, the protecting coating may be left over the segment 55 as indicated in Fig. XI, until after the completed lens has been cut out, edged and if desired placed in the mounting and then the coating removed as the final step in the 60 completion of the lens for visual purposes.

From the foregoing specification taken in connection with the accompanying drawings, the method of construction and structure of my improved semi-finished lens 65 blank should be readily understood, and it

will be seen that I have provided an improved process by which it is possible to produce as a commercial product a two-part bifocal lens in which the major blank and segment are united one to the other by cement but in which a substantially invisible line of joinder between the two parts is obtained. It will further be noted that by the use of my improved process I am able to produce and put out blanks in semi-finished 70 form which can be readily finished in the ordinary prescription shop without liability of damage to or detachment of the segment and which will permit the handling of the lens in the same manner as in ordinary plain 75 meniscus or toric.

It will also be noted that my improved segment cover 9 serves as a retainer for locking the member 6 in correct position within the countersink.

As is well known in connection with the grinding of optical lenses and polishing of same, a greater or less degree of heat is generated and frequently the heating of the lens is sufficient to soften the cementitious 90 medium used in securing the segment within the countersink. This softening is sufficient to cause the cement to act as a lubricant rather than a retaining member so that the segment might have a sliding movement relative to the major blank. On account of the presence of my cover member, however, overlapping the segment and engaging the blank proper circumferentially of the segment, the segment is firmly and securely 95 held against any such accidental sliding movement.

I claim:

1. As an article of manufacture, a semi-finished lens blank, comprising a major portion having a countersink, a segment removably secured within the countersink, the major portion and segment being ground in a continuous even surface on the segment side and a protecting coating secured to said 105 surface and overlying the segment and line of joinder between the segment and the main blank, substantially as and for the purpose described.

2. The process of forming a bifocal lens, 110 including forming a major blank with a countersink, forming a segment to fit within the countersink, securing the segment within the countersink, simultaneously grinding the blank and segment to produce a single 120 curve, placing a protecting coating over the segment, mounting the ground lens on a block, grinding the opposite face of the lens, removing the lens from the block and subsequently removing the coating from the 125 segment and shaping the finished lens.

3. The process of forming a two-part bifocal lens, consisting in securing a segment to one face of a major blank, simultaneously grinding the segment and face of the blank 130

to produce a finished surface on that side of the blank, placing a protecting coating over the segment, grinding the opposite face of the blank, and removing the coating after the 5 grinding operation has been completed.

4. The process of forming a bifocal lens, including securing a segment to one face of the major blank, simultaneously grinding the segment and face of the blank to produce a finished surface, preparing a lens 10 block to receive said surface, mounting the lens on the block with the segment portion

out of engagement with the block, and the surrounding major portion of the lens in engagement therewith, grinding the second 15 surface of the lens, removing the lens from the block and cutting the finished lens from the blank thus formed.

In testimony whereof I have affixed my signature, in presence of two witnesses.

HARRY H. STYLL.
